United States Patent Office

Des. 233,496
Patented Nov. 5, 1974

233,496

BAGGER STATION OR SIMILAR ARTICLE

John David Hunt, Turnersville, N.J., assignor to RCA Corporation

Filed July 12, 1973, Ser. No. 378,518

Term of patent 14 years

Int. Cl. D6—06

U.S. Cl. D6—143

Fig. 1.

Fig. 2.

Fig. 3.

FIG. 1 is a front perspective view of a bagger station or similar article showing my new design,

FIG. 2 is a top plan view thereof,

FIG. 3 is a front side elevation view thereof,

FIG. 4 is a right end elevation view thereof, and

FIG. 5 is a back side elevation view thereof.

The shelf in the lower right of FIG. 1 has been shown fragmentarily for ease of illustration. The rear of the bagger station is unornamented.

I claim:

The ornamental design for a bagger station or similar article, substantially as shown and described.

UNITED STATES PATENT OFFICE
CERTIFICATE OF CORRECTION

Patent No. Design 233,496 Dated January 23, 1975

Inventor(s) John David Hunt

It is certified that error appears in the above-identified patent and that said Letters Patent are hereby corrected as shown below:

After the paragraph beginning "The shelf . . . "
add a new paragraph as follows:

--The broken lines in various ones of the Figures are for illustrative purposes only, and form
no part of the inventive design.--

Add sheet 3 of the drawing which contains Figures 4 and 5.

Signed and Sealed this third Day of February 1976

[SEAL]
